UNITED STATES PATENT OFFICE

2,142,464

REFRIGERATOR

Peter Vassallo, Avalon, N. J.

Application February 21, 1938, Serial No. 191,795

1 Claim. (Cl. 312—182)

This invention appertains to new and useful improvements in refrigerators and more particularly to a refrigerator cabinet in which beer, and other commodities can be kept cool and always handy for sale.

The principal object of the invention is to provide a refrigerating cabinet in which a plurality of cases of beer can be kept subject to a low temperature and readily removed, one at a time, with a minimum loss of cold air from the cabinet.

Another important object of the invention is to provide a refrigerator cabinet in which beer cases are arranged on a conveyor wherein lifting means is provided for lifting the cases one at a time to a restricted opening from which the cases can be singly removed with a minimum loss of cold air.

These and various other important objects and advantages of the invention will become apparent to the reader of the following specification.

In the drawings:—

Figure 1 represents a front elevational view of the cabinet.

Figure 2 is a vertical sectional view taken on the line 2—2 of Fig. 1.

Figure 3 is a horizontal sectional view taken substantially on the line 3—3 of Figure 1.

Figure 4 is a fragmentary vertical sectional view on the line 4—4 of Figure 1.

Figure 5 is a fragmentary enlarged sectional view taken substantially on the line 5—5 of Figure 2.

Figure 6 is a perspective view of one of the slide closures.

Referring to the drawings wherein like numerals designate like parts, it can be seen that the refrigerator cabinet consists of an enclosure made up of the front wall 5, the rear wall 6, the bottom wall 7, the top wall 8, and the side walls 9—9.

As is shown in Figure 4, one side of the interior of the cabinet is provided with a plurality of shelves 10 meeting the sills 11 of openings 12, arranged one above the other as shown in Figure 1. Each of these openings 12 is provided with a slide closure 13 and as is clearly shown in Figure 4, alternate closures are arranged in offset vertical planes with respect to intervening closures so that the closures can be slid vertically to gain access to the corresponding compartment 14 without interfering with the overlying closure, as the closure being opened will overlap the overlying closure. The shelves 10 are preferably constructed of slats and the compartments

14 are separated from the beer case compartment 15 by the partition 17 vertically disposed and which can be likewise constructed of slats if desired.

In the beer case compartment 15 are located a pair of elevator units generally referred to by numeral 18—19. Bearings 20 on the bottom 7 serve to support the shafts 21—21 of the units 18—19 and on these shafts 21—21 are sprocket wheels 22 over which are trained the sprocket chains 23 of the units 18—19.

The assembly 18 is provided with the shaft 24 at its upper end, while the unit 19 is provided with the shaft 25 at its upper end, the shaft 25 being provided with a squared end for accommodating the socket end 26 of the crank 27 which extends through the front wall 5. The shafts 18—19 are provided with bearings 28 and on the shafts 24—25 are sprocket wheels 29 over which the aforementioned chains 23 are trained.

The rear ends of the shafts 24—25 are provided with beveled gears 30 which mesh with the beveled gears 31 on the ends of the counter-shaft 32. Obviously, when the crank 27 is rotated at the front of the cabinet, both elevator units will be operated. To charge the elevator with cases of beer, one case after another is set upon the platform 33. The platform 33 extends across the lower part of the compartment 15 and is spaced from the bottom of the compartment and said platform is located above the lower shafts 21 and their sprockets. The platform 33 is provided with notches 34 in its edge portions through which the lugs 35 can pass and the chains are synchronized so that these lugs are always at the same elevation at different groups to engage a given beer case 36. Therefore, it can be seen that with a case on the platform 33, and the elevator assemblies set in operation, the lugs 35 will engage under the beer case and elevate the same to a point sufficiently high so that another case can be lifted and so on until the entire compartment 15 is charged with cases of beer.

Whenever a case of beer is to be sold, the door 37 at the front of the cabinet can be opened and a whole case pulled out. The elevator is charged with cases through the door 38 at the rear of the cabinet.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:—

5 In a refrigerator having a vertically arranged compartment therein, a platform in the lower part of the compartment and spaced above the bottom thereof, a pair of shafts journaled in the bottom of the compartment below the platform, a pair of sprockets on each shaft, a second pair of shafts journaled in the upper part of the 10 compartment, a pair of sprockets on each second shaft, chains passing over the sprockets of the upper and lower shafts, outwardly extending lugs carried by the chains, said platform having notches in its side edges for the passage of the

chains and the lugs, said lugs adapted to engage an object placed on the platform to lift said object, a counter shaft journaled in the upper part of the compartment, gears connecting each end of said counter shaft with one end of an upper shaft, a crank handle journaled in a side wall of the refrigerator and engaging an opposite end of one of the upper shafts, said refrigerator having an opening therein for placing articles on the platform and a second opening for removing an object from the upper portions of the chains, and doors for closing said openings.

PETER VASSALLO.
